UNITED STATES PATENT OFFICE

JOSEPH A. KENNEDY, OF PAWTUCKET, RHODE ISLAND, ASSIGNOR TO ANACONDA WIRE
AND CABLE COMPANY, OF NEW YORK, N. Y., A CORPORATION OF DELAWARE

TUBING FOR ELECTRICAL PURPOSES

Application filed May 20, 1929. Serial No. 364,517.

This invention relates to tubing adapted to be used as electrical conduit to receive and protect electrical wiring and other conductors. One particular object has been to provide a tubing or conduit of this character applicable to automobiles for encasing the wires of the electric light and power circuits. To meet the needs of such service in the fullest manner the tubing must be impervious to penetration and resistant to attack and modification by water, oil, gasoline and the acid electrolyte of storage batteries, and must also have a pleasing finish and appearance so that when used in positions exposed to view on the car, as to encase the wires leading to the lamps, it will not detract from the beauty of the car as a whole, but will harmonize with the finish and color effect of the car. In addition it must have the commonly required qualities of electrical conduit such as adequate tensile strength, flexibility to permit bending in curves, and adequate stiffness to resist collapse under lateral pressure and such flattening or kinking as would obstruct its bore when bent on a curve.

In realizing my object, I have produced a tube having all the characteristics above named and including a smooth, lustrous finish on the outer surface. A series problem in this connection was to determine how to cover and obscure the rugosity of the tube without impairing its strength and flexibility. The solution of this problem and other characteristics and features in which the invention consists are explained in the following specification in connection with the drawing.

The single figure of the drawing shows a fragment of a tube embodying the invention and represented partly in a dismembered condition and partly in its finished state.

The foundation, base or body of my new product is a seamless tube *a* composed of flexible cotton warp strands *b* and helical weft or filling strands *c* of tightly twisted paper or other suitable material having desirable qualities of strength and stiffness constructed and combined by known methods of circular weaving; substantially like the tube shown in the patent to Charles S. Smith

No. 1,016,527, dated February 6, 1912, but with possible variations in relative proportions of the elements. Its strands are made water-repellent and stiffened by saturation or impregnation with a suitable substance for that purpose carried in solution or suspension by a volatile liquid vehicle; for example, I prefer to use for that purpose a hard asphalt dissolved in volatile solvent and thinned to a consistency resembling water, or I may use an emulsion of asphalt in water or other non-solvent. Whatever may be the vehicle and however the waterproofing agent may be associated with the vehicle, the agent is caused to permeate throughout the strands of the fabric and into and among the pores and fibers of such strands. The tube is then dried, preferably in an oven under artificial heat whereby the solvent or liquid vehicle is driven off and the residuum of asphalt or the like is dried and baked. This greatly increases the capacity of the tube to resist collapsing while leaving it still sufficiently flexible for the purposes in view.

A tube so made is inevitably rough on the surface, for the filling strands necessarily have substantial thickness, and the warp strands, being bent around the filling strands, form distinct wales or ridges with shallow grooves or valleys between them.

Then in order to cover this roughness and provide a relatively smooth surface as a ground for the outer finishing compound, I wrap the tube *a* with a number of fine strands *d* of cotton yarn or equivalent material, laid side by side and wound in parallel helices with a pitch opposite to that of the helical weft strands. These strands are laid under such tension that they bridge across the grooves or valleys of the tube structure and are so fine and laid so closely together that they form virtually a smooth surface, or at least so nearly approach a smooth surface that the finished surface coating which is afterward laid on them is almost perfectly smooth.

The threads or strands *d* are impregnated with a compound of the same nature as that with which the body tube is impregnated, and dried before winding. This is done in order

that they shall not absorb any of the compound from the body tube and so diminish the perfection of saturation and water repellence of the latter. And it is also important that the wrapping strands be adherently united to the body tube so that they will not be displaced and tend to roughen the finished surface when the tube is bent on a curve. The cement or adhesive material for this purpose must be strong, tough and tenacious and remain firm and non-fluid, after having set, even when subjected to heat considerably above the temperature of the atmosphere. Compositions of several classes may be used, such as stearin pitch, asphalt, gums, glues, etc. A suitable gum to use is Manila gum dissolved in alcohol and containing a small proportion of castor oil to give it flexibility after drying. However, at the present time I consider a treatment with emulsified asphalt and stearin pitch best suited for these purposes. To illustrate a suitable shop practice for applying this treatment, I may say that the tube is first treated with melted stearin pitch and drawn to the proper external diameter. Then during the operation of wrapping the outer strands, the tube is passed through a bath of emulsified asphalt. This treatment gives the desired adhesion of the wrapping strands but without making the tube unduly stiff. All excess of each solution is wiped off and the residue allowed to dry or set before the final coating treatment is applied.

Finally, the wrapped tube is externally coated with oil-resistant and acid-resistant lacquer. I have found suitable for use for this purpose a solution of a cellulose compound, as nitrocellulose, viscose, cellulose acetate, etc. in a suitable solvent. I do not claim any novelty in the lacquer itself, but may use any one of a number of lacquers now on the market which have sufficient flexibility to withstand bending and temperature changes without cracking or pulling away from the layer of wrapping yarns. The lacquer solution is applied by passing the tube through a bath and wiping off the excess by means of a ring shaped die through which the tube passes. The film left adhering is allowed to dry and additional films are similarly applied to any desired number, until a coating of the desired thickness is built up.

The lacquer dries with a bright glossy surface, and may be given any desired color by admixture of suitable pigment or dye. Hence the tubing may be finished with an ornamental quality conforming or harmonizing with the brilliancy and various color schemes of automobiles.

The tubing made according to the principles herein described has great tensile strength due to the numerous longitudinal warp strands; substantial resilient stiffness

to resist collapse due to the initial stiffness of the helically arranged filling or weft strands, and the additional stiffness imparted to them by the waterproofing compound with which all the strands are impregnated; and flexibility sufficient to permit bending on a curve. It is impervious to penetration and deterioration by oil, gasoline, acid and water; being made so by the outer coating or sheath of acid-, oil- and water-resistant lacquer, and by the impregnation of the body tube by the waterproofing compound from which oil and acid are excluded by the outer coating. And it is made additionally resistant to collapse, as well as smooth on the outside by the wrapping of fine yarns and the lacquer coating.

It should be noted that the conduit of this invention, while particularly suited and desirable for use in and about automobiles, is not limited to such use but is adapted to contain and protect insulated wires in other situations as well; and that the naming of specific substances and compounds is not necessarily a limitation to such compounds, etc., otherwise than as indicated by the claims.

What I claim and desire to secure by Letters Patent is:

1. Tubing for electrical purposes comprising a seamless woven body tube having interwoven longitudinal warps and helical filling, a wrapping of fine yarns wound helically with pitch of opposite inclination to the filling, and an outer layer of lacquer on said wrapping. 95
2. Tubing for electrical purposes comprising a seamless woven body tube having interwoven longitudinal warps and helical filling, a wrapping of strands finer than the filling laid side by side and wound helically with opposite inclination to the filling so as to bridge across the external wales of the tube and being adherently secured thereto, and an outer layer or sheath of flexible cellulosic lacquer. 105
3. Electrical conduit having resilient strength resistant to collapse and being flexible and resistant to penetration and deterioration by water, oil and acid, comprising a woven body tube having continuous helical weft strands of twisted paper and being impregnated with a stiffening water-repellent material, a wrapping consisting of a number of fine yarns impregnated with the same composition and being laid side by side and wrapped helically about the body tube with a pitch or inclination opposite to that of the said weft strands, crossing the helical ridges of the body tube and being adhesively bonded thereto, and an outer coat or sheath of cellulosic lacquer deposited on and enveloping said wrapping. 115

4. Electrical conduit consisting of a body tube made of interwoven longitudinal warp strands and helical weft strands, saturated 130

with a dried waterproofing compound which has substantial stiffness in the dry condition, a wrapping of fine yarns laid closely side by side and wound helically about the tube crossing the ridges formed by the weave of the tube and adhesively bonded thereto, and an outer layer or sheath of lacquer which is impervious to oil deposited on and bonded to said wrapping yarns.

5 10 In testimony whereof I have affixed my signature.

JOSEPH A. KENNEDY.
